UNITED STATES PATENT OFFICE

HENRY W. MORGAN, OF BRIGHTON, NEW YORK, ASSIGNOR TO MORGAN MACHINE COMPANY, INC., OF ROCHESTER, NEW YORK, A CORPORATION OF NEW YORK

NAILING MACHINE

Application filed October 12, 1931. Serial No. 568,360.

The present invention relates to a nailing machine and has for its object to provide an improved machine of this class for operating upon different forms of work and embodying 5 a simple and practical arrangement of parts which is comparatively inexpensive to manufacture and efficient in operation.

A further object of the invention is the provision of improved means for positioning 10 work pieces which are to be attached, as for example, by nailing to different or similar forms of work.

A further object of the invention is to provide improved work positioning means in 15 which the operating mechanism for positioning the work is properly timed with respect to other means for operating upon the work, such for example, as an automatic nailing device.

20 A still further object of the invention is to provide improved means for positioning cleats, strips, and the like at points relatively inaccessible in order that they may be attached as by nailing, to other forms of work, 25 and to construct said means so as to insure positive and uniform operation of the parts with proper adjustment to accommodate work pieces of different dimensions.

To these and other ends the invention resides in certain improvements and combinations of parts, all as will be hereinafter more fully described, the novel features being pointed out in the claims at the end of the specification.

35 In the drawings:

Fig. 1 is a fragmentary end elevation of a nailing machine embodying the invention, the parts being in their normal position ready for application of the work thereto;

40 Fig. 2 is a similar view with the work in position and being operated upon by the nail driving means, the main frame being broken away to show the cam for operating the work positioning mechanism;

45 Fig. 3 is a horizontal section with parts broken away to show certain elements of the cam operated mechanism;

Fig. 4 is a fragmentary sectional elevation taken substantially on line 4a—4a of Fig. 3;

50 Fig. 5 is a sectional elevation through an

operating connection for the work positioning means, drawn to an enlarged scale and taken on line 5a—5a of Fig. 2;

Fig. 6 is a sectional elevation drawn to an enlarged scale, taken on line 6a—6a of Fig. 2 55 and illustrating the construction of the rocker for moving the work positioning means;

Fig. 7 is a vertical section illustrating details of the operating means for the work positioning members; 60

Fig. 8 is a vertical section substantially on line 8a—8a of Fig. 9, and

Fig. 9 is a transverse section substantially on line 9a—9a of Fig. 7.

Similar reference numerals throughout the 65 several views indicate the same parts.

The invention illustrated in the drawings while adapted for use in the positioning of different classes of work to be operated upon, is particularly designed for positioning relatively narrow sections of material at predetermined points for attachment to other forms of work, as for example, sheets of veneer or other board-like material. The positioning means is not only adjustable to take 70 care of slight variations in the width or thickness of the work pieces, but may be adjusted to accommodate work pieces of different size varying between predetermined limits as 75 pointed out hereinafter.

80 Referring to the drawings, 10 represents the upright standards or frame members of a nailing machine, the standards being provided with guideways 11 on their front faces. A work support 12 preferably in the form of 85 a table is arranged for adjustment up and down on the guideways in accordance with the thickness of the work to be operated upon by suitable adjusting means, not shown.

The nailing mechanism may be of any suitable type, and preferably comprises a nailing head 14 having a series of nail drivers or plungers 15 for operation within suitable chucks 16 on a holding device 17, the chucks being supplied with nails by tubes 18 leading 90 from an overhead nail hopper, not shown.

95 The nailing head and chuck holding device are reciprocated upon the guideways 11 by means of a pair of connecting rods 19, the upper ends of the rods engaging pivot pins 100

- 20 on the nailing head having rollers 20a thereon and the lower ends of the rods being connected to eccentric straps 21 on a pair of eccentrics 22 fixed to a shaft 23 driven by 5 suitable means not shown, operating to effect a single revolution of the shaft for each nail driving operation. When the shaft is rotated in a clockwise direction from the position shown in Fig. 1, the rods 19 are drawn 10 downwardly and operate to pull down the nailing head 14. Upon downward movement of the rods the rollers 20a, which extend into suitable cam slots in levers 24 pivotally connected at 24a with the standards 10, cause the 15 levers to swing downwardly. The chuck holding device 17 is connected with the levers by means of a pair of rods 25 surrounded by coiled springs 26 which cause the chuck holding device to move downwardly until the 20 chucks 16 come in contact with the top of the work to be operated upon, such as the sheet of veneer 27 which overlies and is to be nailed to a cleat 28 on the table 12. After the chuck engages the top of the work and comes to 25 rest thereon, the links 19 are permitted to continue their downward movement by reason of further compression of the springs 26 and thus the driving head 14 will operate the nail driving plungers 15 to drive the nails into the 30 work.
- Where it is desired to drive the nails through a work piece of relatively large area such as the sheet of veneer 27 into another work piece therebeneath, such as the cleat or batten 28, the larger work piece prevents convenient access to the smaller work piece and it is therefore difficult for the operator to satisfactorily position the latter by hand. The present invention embodies mechanism 35 operable automatically to position the lower work piece in proper relation to the overlying work piece, which mechanism operates beneath the overlying work piece without displacing or interfering therewith.
- 40 A suitable stop 29 for the work is mounted on the support 12 to properly position the work, the stop being adjustable whereby to vary the distance of the nails from the edge of the work. When the back stop has been 45 adjusted to the desired position the work 28 may be moved into contact therewith by the mechanism provided where it will be ready to receive the nails to be driven therein.
- The work positioning means comprises a 50 plurality of finger-like members constituting pusher bars 31 located beneath the table and having their free ends resting upon inclined faces 32 of the table which form the inclined bottom surfaces of the slots 33 formed in the 55 table, the side walls 32a of the slots serving to guide the fingers from the lowered position shown in Figs. 1 and 7 to the elevated operating position shown in Fig. 2. The inclined faces 32 serve as raised means for the 60 work engaging ends of the fingers when they

are moved rearwardly and during this time the fingers will move through the openings and engage the work pieces lying on the table near the rear edge thereof to position them against the back stop 29, thus properly positioning the work with respect to the overlying work piece 27 beneath which the fingers operate. 70

The front ends of the fingers lie between the jaws 34 and 35 of the vertical operating arms 36 fixed on a rock shaft 37 beneath the table, the fingers being supported between said jaws by pivot pins 38 as best shown in Fig. 9. The pin in each case is provided with a movable handle portion 39 and can be released by gripping said portion and moving the pin longitudinally which at this time is released by a plunger 40 within the jaw 34 of the arm and held in engagement with the pin by a light spring 41. The plunger and spring are supported by a detachable plug 42 threaded within the jaw 34, Fig. 9. The pin is provided with a longitudinal groove 43 at the ends of which are provided notches 44 and 45 for receiving the end of the plunger 40 which holds the pin against accidental displacement. If for any reason it is desired to disconnect the fingers from the arms, the pins 39 can be shifted from the position shown in Figs. 4 and 9 by an outward pull thereon and as soon as the pin is moved to a position at which the notch 45 is in registry with the plunger 40, the latter will move into the notch and secure the pin in position to permit withdrawal of the finger. With this arrangement the fingers can be quickly attached to and removed from the operating arms without completely removing the pin, which otherwise might become lost or misplaced. 95

100 The rock shaft 37 has its opposite ends journaled in suitable bearings 46 carried by the vertically extending plates 47 on the underside of the table 12 as best shown in Figs. 1 and 4. The rock shaft carries a depending operating device 48 comprising a pair of connected members held on the shaft by a key 49 and spaced apart at their lower ends to receive a nut 50 having trunnions 51 at its opposite sides journaled in the arm-like portions of the device as shown in Fig. 6. The nut has adjustable therein a screw 52 provided with oppositely disposed longitudinally extending slots 53 for receiving the upper end of a gravity actuated latch 54 pivoted at 55 between lugs 56 on the nut 50, as best shown in Fig. 5. The latch is for the purpose of preventing accidental turning of the screw after it has once been properly adjusted. The screw may be released for 110 turning by moving the lower end of the latch to the left of the position shown in Fig. 5 and when the latch is thereafter released it will be swung back to latching position by the action of gravity, assuming of course that 115 120 125 130

one or the other of the slots 53 of the screw has been brought into registry with the upper end of the latch. The screw is operated by a hand wheel 52a which is secured against 5 turning relative to the screw by a key 53a, Fig. 5. The hand wheel can be gripped by the fingers and turned to adjust the screw for the purpose of regulating the position of the arms 36 to obtain the proper movement 10 of the work positioning fingers 31 in order to regulate the pressure against the work pieces 28 and to accommodate the fingers to cleats of different sizes within certain limits when moving the cleats in contact with the 15 back stop 29. A certain degree of adjustment may be effected by means of the screw by reason of the oppositely disposed slots 53 which permit of a half turn adjustment of the screw.

20 Extending through the screw 52 is an operating rod 57 having on its outer end a nut 58 seated on a flexible washer 58a disposed on the outer end of the screw to afford a comparatively noiseless operation when the rod 25 is returning to the position shown in Fig. 5. The rear end of the rod is disposed between the jaws of an operating arm or lever 59 and connected therewith by a pivot pin 60 carried by said jaws. A spring 61 surrounds the rod 30 and has one end seated on a bearing 62 on the inner end of the screw. The opposite end of the spring is seated on a nut 63 on the threaded portion of the rod, the nut being adjustable to properly tension the spring whereby to 35 regulate the pressure of the fingers 31 against the work piece 28. A lock nut 64 is provided on the rod for holding the nut 63 against displacement.

40 The lever 59 for operating the work positioning parts is supported by a pivot member 65 carried by the laterally extending arms 66 of a bracket 67 suitably connected with the frame of the machine. Operation of the lever 59 is afforded by means of a suitable 45 cam 68 fixed on the shaft 23 which operates the links 19 and nail driving head 14. The lever carries a pivot pin 69 on which is mounted a roller 70 projecting within the groove 71 of the cam, the cam being designed 50 to operate the lever and the parts actuated thereby, including the work positioning fingers in proper timed relation with respect to the driving operations of the nailing mechanism.

55 The spring 61 on the operating rod 57 will if the work positioning fingers should encounter any obstruction tending to prevent further movement thereof, yield sufficiently to avoid breaking of the parts. It will be 60 understood that the rod 57 is free to slide within the screw 52 so that on the outward stroke of the rod the nut 58 will move away from its seat on the washer 58a but on the return stroke the nut will engage the washer 65 and positively return the operating parts, in-

cluding the arms 36 and fingers 31 to normal inoperative position, as shown in Fig. 1.

One of the important features of the invention embodies the idea of operating the work positioning fingers 31 through slots in the table by means of the rock shaft 37 carrying the arms 36 and fingers pivotally mounted thereon as described above. This is a simplified and very practical and efficient arrangement which is operated with a single harmonic cam, through the medium of the lever 59, arm 48, and yieldable connection shown in Fig. 5 between the arm and lever. The parts driven by the cam are all located beneath the table and in advance of the upright frame members so that they do not interfere with the operator's movements but at the same time being readily accessible and easy to assemble and repair while avoiding the disadvantages of protruding parts projecting beyond the body or framework of the machine. With this arrangement, the fingers 31 are permitted to swing about their pivotal axes while moving to advance the work, as distinguished from a sliding non-pivotal movement in a straight path. With the present arrangement therefore, the inner or free ends of the fingers are substantially horizontal when in work holding position, as shown in Fig. 2, and the pressure is thus applied at right angles to the axis of the nail driving plunger, which is both desirable and advantageous.

55 The manner of mounting the pivot pins 38 as shown in Fig. 9 is a highly desirable improvement, since it permits of quick detachability of the work positioning fingers without having to remove the pivot pins, which can be readily adjusted to release position, in which the plunger 40 will engage in notch 45 and also readily move into holding position as shown in Fig. 9.

60 The improvements embodied in the resilient connection between the operating lever 59 and the rocker arm 48 previously described, not only serve to prevent breakage of the parts, should the fingers operated thereby encounter obstructing means tending to prevent normal operation thereof, but is of a nature to afford a considerable range of adjustment 65 to take care of variations in the dimensions of the work operated upon by the fingers. A further advantage in this resilient connection lies in the particular manner of mounting the adjusting screw 52 to permit of easy operation 70 thereof without undue pressure by the spring on the threads of the screw as pointed out above.

65 In operation of the machine the cleat or work piece 28 is positioned on the table or support 12 adjacent the stop 29 and the sheet or board 27 is then placed in position as shown in Figs. 1 and 2. If the work piece 28 is not in proper position against the stop 29, the fingers 31 upon being advanced during op-

eration of the nailing machine will move said work piece into engagement with the stop as shown in Fig. 2. Advancement of the fingers will be afforded at the proper time upon operating a clutch or other driving means for the shaft 23, not shown, which affords a complete revolution of the shaft from the position shown in Fig. 1. This will cause the driving head 14 and chuck holding device to move downwardly and at the same time the cam 68 will rock the shaft 37 to advance the work positioning fingers which movement is preferably completed prior to the time the chucks are moved into engagement with the work piece 27 so that the work positioning members will not have to operate against the resistance which would be caused by contact of the chuck with the work in advance of the positioning operation. A dwell on the cam holds the work positioning means in the effective position shown in Fig. 2 while the chucks and nail driving plunger complete their operation, after which the cam relieves the work positioning mechanism and the parts are returned to normal position.

While one embodiment of the invention has been shown and described, it will be understood that the invention is not limited to the specific arrangement of parts disclosed, but is intended to cover different variations and modifications falling within the spirit of the invention or the scope of the appended claims.

I claim:

- 35 1. In a nailing machine, the combination of a frame, a work support thereon having a part inclined to the horizontal nailing mechanism movable upon the frame to engage a work piece overlying the support to secure it to a second work piece movable beneath the first, an oscillatory member beneath the support, a positioning member having one end arranged upon said inclined part for elevation thereby adapted to engage and move said second work piece to a predetermined position beneath the overlying work piece and having its other end operatively engaged by said oscillatory member, and means for actuating said nailing mechanism and said oscillatory member in proper timed relation.
- 40 2. In a nailing machine, the combination of a frame, a work support thereon provided with a stop for the work, nailing mechanism movable upon the frame, driving means operatively connected with the nailing mechanism, an oscillatory member beneath the work support having an upstanding portion thereon, a push bar slidably upon the support and connected with said portion for direct operation thereby and operable through the latter to move a work piece on the support into engagement with said stop, and means actuated by said driving means for operating said oscillatory member.
- 45 3. In a nailing machine, the combination

of a work support, nailing mechanism, operating means for said nailing mechanism, a rock shaft, arms carried by the rock shaft, work positioning members individually connected with the arms at one end and having their opposite ends extending from a point below the support upwardly through an opening therein and free to move upon the support to position the work thereon, and means for oscillating said rock shaft arranged to be actuated by the operating means for the nailing mechanism in timed relation to said nailing mechanism.

4. In a nailing machine, the combination of a frame, a work supporting table thereon, nailing mechanism movable upon the frame, operating means for said nailing mechanism, a rock shaft spaced below the table, arms extending upwardly from the rock shaft beneath the table, a positioning member connected with each arm, said members having their work engaging ends arranged for operation through openings in the table to engage and position the work on the latter, and means for oscillating the said rock shaft arranged to be actuated by the operating means for the nailing mechanism in time relation with respect to said nailing mechanism.

5. In a nailing machine, the combination of a frame, a work supporting table having a work stop thereon, nailing mechanism movable upon the frame, operating means for the nailing mechanism, a rock shaft spaced below the table, arms extending upwardly from the rock shaft beneath the table, work positioning members beneath the table each directly connected with one of the arms at one end and having their opposite ends supported by the table and arranged for upward movement thereby through openings formed therein to an elevated position whereby to move the work into engagement with said stop, and means for oscillating said rock shaft.

6. In a nailing machine, the combination of a frame, a work supporting table having a work stop thereon, nailing mechanism movable upon the frame, operating means for the nailing mechanism, a rock shaft spaced below the table, arms extending upwardly from the rock shaft beneath the table, work positioning fingers beneath the table each operatively connected with one of the arms at one end, said fingers having their opposite ends supported by the table for movement upwardly thereby through openings formed therein to an elevated position whereby to move the work into engagement with said stop, a cam driven by the operating means for the nailing mechanism, a lever actuated by the cam, and an operating member on the rock shaft and yieldable operating means between the lever and said operating member for moving the latter to operate the rock shaft.

7. In a nailing machine, the combination of a frame, a work support thereon having a part below its upper surface inclined to the horizontal, a work stop on the support, a nailing mechanism movable upon the frame to engage a work piece to secure it to a second work piece disposed therebeneath on the support, a vertically disposed member mounted for oscillation beneath the support, 70 a substantially horizontal push bar beneath the support having one end directly connected with said member and its other end resting on and arranged to be elevated by said inclined part of the support to a position 75 above the support during advancement of the push bar whereby to move said second work piece into engagement with said stop, and resilient operating means for said member.
8. In a nailing machine, the combination of a frame, a work support thereon having a part below its upper surface inclined to the horizontal, a work stop on the support, nailing mechanism movable upon the frame to engage a work piece to secure it to a second work piece disposed therebeneath on the support, a vertically disposed member mounted for oscillation beneath the support, a substantially horizontal push bar beneath the support having one end operatively engaged by said member and its other end resting on and arranged to be elevated by said inclined part of the support to a position above the support during advancement of the push bar 80 whereby to move said second work piece beneath the first into engagement with said stop, an operating connection for said arm adjustable to vary its position with respect to said work stop, an operating member for reciprocating said connection, a cam operatively connected with said member, and a drive shaft operatively connected with said nailing mechanism said cam being driven by said shaft in proper timed relation to said nailing mechanism. 85
9. In a nailing machine, the combination with a work support having a stop thereon for the work and nailing mechanism for operating upon the work, of positioning mechanism for a work piece on the support comprising an element operable to move said work piece into engagement with the stop, and relatively movable operating devices for said element having an operating connection therebetween comprising a member adjustably mounted on one of said operating devices 90 to vary the effective length of said connection, a rod connected with the other of said operating devices and slidably mounted in said member, and means operating to yieldingly resist movement of the rod during movement 95 of the parts to operating position. 100
10. In a nailing machine, the combination of a frame, a work support thereon having a part below its upper surface inclined to the horizontal, a work stop on the support, a nailing mechanism movable upon the frame to engage a work piece to secure it to a second work piece disposed therebeneath on the support, a vertically disposed arm mounted for oscillation beneath the support, a substantially horizontal push bar beneath the support having one end operatively connected with said arm and its other end resting on and arranged to be elevated by said inclined part of the support to a position above the support during advancement of the push bar whereby to move said second work piece beneath the first into engagement with said stop, an operating connection for said arm comprising parts adjustably one longitudinally of another to vary the effective length of the connection, a lever operatively engaging the connection, a cam for operating the lever, and driving means for said cam. 110
11. In a nailing machine, the combination with a work support having a stop thereon for the work and nailing mechanism for operating upon the work, of positioning mechanism for a work piece on the support comprising an element operable to move said work piece into engagement with the stop, and relatively movable operating devices for said element having an operating connection therebetween comprising a member adjustably mounted on one of said operating devices to vary the effective length of said connection, a rod connected with the other of said operating devices and slidably mounted in said member, and means operating to yieldingly resist movement of the rod during movement 115 of the parts to operating position. 120
12. In a machine of the class described, positioning means for a work piece to be operated upon by a nail driving mechanism, including a positioning element and relatively movable operating parts therefor having a resilient operating connection therebetween comprising a screw adjustably mounted on one of said parts, an operating rod for the screw connected at one end with the other of said parts and having a limited movement within the screw, an abutment on the rod, spring means interposed between the abutment and the screw tending to urge them in opposite directions, and a releasable locking member for holding the screw against turning. 125
13. In a machine of the class described, positioning means for a work piece to be operated upon by a nail driving mechanism, including a positioning element, relatively movable operating parts therefor having a resilient operating connection therebetween comprising a nut having trunnions thereon journaled in the walls of one of said oper- 130

ating parts, a screw threadedly engaging the nut, an operating rod connected at one end with the other of said parts and extending through the screw and provided at its free end with an abutment, spring means on the rod tending to move the rod and screw in opposite directions, means adjustable on the rod to vary the tension of the spring means, said screw having one or more longitudinally extending grooves therein, and a gravity operated latch arranged to enter the groove in a predetermined position of the screw whereby to hold the screw against turning.

14. In a nailing machine of the class described, a support for holding a work piece, means for moving the work piece to a predetermined position upon the support comprising a vertically disposed rocker arm at one side of the support having spaced jaws at its free end, a push bar for positioning the work piece upon the support having one end extending between the jaws of said rocker arm, a pin pivotally receiving said push bar end between said jaws, said pin having a longitudinally extending groove therein and notches adjacent the ends of the groove, and a spring pressed plunger in one of said jaws normally engaging said pin in one of the notches to hold it in position to support said push bar, said pin being adjustable by a sliding movement between predetermined release and holding positions and said plunger moving automatically into the notches of the pin when adjusted to said positions, the pin being held against turning by the plunger in all positions of the latter.

15. In a nailing machine of the class described, positioning means for a work piece to be operated upon by a nail driving mechanism forming a part of the machine, comprising an oscillatory member, operating means for said member, a second member comprising a push bar for positioning said work piece, a pin pivotally connecting said members and slidably mounted in the walls thereof between operating and release positions, said pin having a longitudinally extending groove and having notches at the ends of the groove, and a spring pressed member movable relative to the pin adapted to engage it within the groove when the pin is moved between said positions whereby to hold it against turning and adapted to automatically move into the notches when in registry therewith to arrest movement of the pin at said different positions.

16. In a nailing machine, the combination with a work supporting means having stop means thereon for the work, of nailing mechanism for driving nails into the work, a work engaging member normally spaced laterally from the work at a point below the surface of the supporting means, and control means for moving the work engaging member in a vertical direction and simultaneously recip-

rocating it transversely of said direction to cause it to move into engagement with the work and to be withdrawn therefrom to normal position below the surface of the supporting means, said control means including an oscillatory operating part for the work engaging member extending upwardly beneath the work supporting means and directly connected with said work engaging member, said operating part moving in timed relation to the operation of the nailing mechanism.

17. In a nailing machine, the combination with a frame, a work support adjustable upon the frame, of nailing mechanism for driving nails into the work, work engaging and positioning means normally spaced laterally from the work at a point below the surface of the support and movable bodily with the support upon adjustment of the latter upon the frame, and control means for moving the work engaging means in a vertical direction and simultaneously reciprocating it transversely of said direction to cause it to move into engagement with the work and to be withdrawn therefrom to normal position below the surface of the work supporting means, said control means including an oscillatory operating part for the work engaging and positioning means extending upwardly beneath the work supporting means and directly connected with said work engaging and positioning means, said operating part moving in timed relation to the operation of the nailing mechanism.
